Attoys.

UNITED STATES PATENT OFFICE.

JOHN A. LAMONT, OF CHICAGO, ILLINOIS, ASSIGNOR TO AMERICAN STEEL FOUNDRIES,
OF CHICAGO, ILLINOIS, A CORPORATION OF NEW JERSEY.

RAILWAY-TRUCK ARRANGEMENT.

1,377,703.

Specification of Letters Patent. Patented May 10, 1921.

Application filed November 8, 1920. Serial No. 422,463.

To all whom it may concern:

Be it known that I, JOHN A. LAMONT, a citizen of the United States, residing at Chicago, in the county of Cook and State of Illinois, have invented certain new and useful Improvements in Railway-Truck Arrangements, of which the following is a specification.

This invention relates to a railway truck arrangement.

One object of the invention is to simplify and improve journal box constructions and their coöperative association with side frames to produce an efficient arrangement.

Another object is to provide a truck side frame and journal box with simple and improved spring-receiving portions.

A further object is to provide a simple and efficient truck arrangement including a truck side frame, journal box and springs which coöperate in an improved manner to meet various requirements for successful commercial use.

These and other objects are accomplished by means of the arrangement disclosed on the accompanying sheet of drawings, in which—

Figure 1 is a fragmentary side elevation of a railway car truck, parts being in section, embodying my invention;

Fig. 2 is a top plan view of my improved journal box showing a wearing band secured thereto; and

Fig. 3 is a perspective view of the wearing band which is interposed between the journal box and side frame.

The various novel features of my invention will be apparent from the following description and drawings and will be particularly pointed out in the appended claims.

Referring to the figures of the drawings, it will be noted that my invention is illustrated in connection with a railway car truck including a truck side frame 10 having a plurality of spring pockets 11 which coöperate with laterally extending bracket portions 12 of a journal box 13 for receiving concentrically arranged coil springs 14 and 15, the former being the heavier springs and surrounding the latter relatively light coil

springs. Each spring pocket of the side frame is formed by a depending closed wall the depth of which varies, the minimum depth being at the outer side as shown at 16 and the greatest depth being shown at 17. The inner walls 17 of the spring pockets 11

serve as journal box guides for guiding the journal box 13 in its relative vertical movements with respect to the side frame 10. For reducing the wear of the relatively moving parts, a hardened steel band 18 is slipped over the main portion 19 of the journal box and extends down the sides thereof and then extends laterally outwardly over the bracket portion 17 of the journal box to which said wearing plate is secured by means of rivets 20. This wearing plate 18 is provided with a slot 21 which receives the top strengthening rib 22 of the journal box whereby the wearing plate is held in a given position with respect to the journal box. The vertical portions of the spring wearing plate 18 are interposed between the relatively moving spring pocket walls 17 and the journal box. The side frame has depending lugs 21' each of which fits within the upper end of its associated light coil spring 15 and forms means for retaining the springs in a given position within said box. The upper head of each of the rivets 20 extends upwardly a slight distance within the inner coil spring 15 and as a result thereof tends to center the springs on the brackets 12. The coil springs 14 and 15 are substantially inclosed within the side frame pockets 11 and by the oppositely arranged side flanges 23 of the journal box, said flanges 23 increasing in height from their outer extremities toward the middle of the journal box. These strengthening flanges 23 also serve to retain the relative lateral position of the journal box with respect to the side frame as a result of the overlapping association of said journal box side flanges 23 and adjacent portions of the side frame.

It is my intention to cover all modifications of the invention falling within the spirit and scope of the following claims.

I claim:

1. In a railway car truck, a truck side frame having an integrally formed wall portion forming a depending pocket for the reception of a spring at the side of an associated journal box.

2. The combination of a truck side frame having an integrally formed wall portion forming a depending spring pocket, one wall of which acts as a journal box guide.

3. In a railway car truck, the combination of a truck side frame, a journal box having laterally extending brackets, there

- being side walls connecting said brackets for increasing the carrying capacity of said box, and springs interposed between said brackets and a portion of said side frame, said side frame having a spring retaining wall located within said side walls.
4. In a railway car truck, the combination of a side frame having depending spring pockets, a journal box having laterally extending brackets and side walls connecting same, the walls of said spring pockets forming guides for said journal box, and springs resting in said pockets and mounted upon said journal box brackets.
5. In a railway car truck, the combination of a truck side frame having spring pockets, a journal box having laterally extending brackets and side flanges, said flanges extending over the journal receiving portion of the box, and springs mounted in said pockets and resting upon said journal box brackets and being substantially inclosed within said pockets and journal box flanges.
6. In a railway car truck, a journal box having a main journal-receiving portion and laterally extending brackets, and a wearing plate capping said box and covering said laterally extending bracket portions.
7. In a railway car truck, a journal box having laterally extending brackets with side walls extending over the journal receiving portion for increasing the load capacity of said box and limiting movement of an associated side frame in one direction.
8. In a railway car truck, a journal box having laterally extending brackets with side walls extending over the journal receiving portion for increasing the load capacity of said box and limiting movement of an associated side frame in one direction, and reinforcing means extending below the journal receiving portion of the box and connecting said brackets.

Signed at Chicago, Illinois, this 4th day of November, 1920.

JOHN A. LAMONT.
